UNITED STATES PATENT OFFICE.

HARRY S. FRANK, OF ST. LOUIS, MISSOURI, ASSIGNOR TO INLAND MACHINE WORKS,
OF ST. LOUIS, MISSOURI, A CORPORATION OF MISSOURI.

PROCESS OF MAKING PISTON-RINGS.

1,283,138.

Specification of Letters Patent. Patented Oct. 29, 1918.

Application filed September 11, 1916. Serial No. 119,370.

To all whom it may concern:

Be it known that I, HARRY S. FRANK, a citizen of the United States, residing at the city of St. Louis and State of Missouri, 5 have invented a new and useful Improvement in Processes of Making Piston-Rings, of which the following is a specification.

This invention relates to the art of manufacturing piston rings, and its consists in the 10 process of manufacturing and characterizing piston rings so that when applied to use within a cylinder the pressure of the rings against the cylinder will be equally distributed and proportioned throughout their 15 circumference.

An object of the invention is to provide a novel process for use in the art of manufacturing piston rings, whereby rings of uniform radial thickness may be produced. 20 and so characterized that, when compressed within the cylinder for which they are intended, they will impart against the cylinder wall a uniform pressure all around, without variation in the pressure as in the 25 case of rings of usual construction.

Another object of the invention is to provide a process of manufacturing and characterizing piston rings of the open resilient type and of uniform thickness all around, 30 whereby the stresses of the rings opposite the cuts, and the pressure of the rings against the cylinder walls throughout their circumference, are properly proportioned or equalized throughout the circumferential 35 portions of the rings. This characterization of the rings and the equalization of the stresses and pressure are attained in rings of the split construction, as well as in rings possessing any of the well known cuts, such, 40 for instance, as the straight, diagonal, or lap-joint cuts.

Another object of the invention is to provide a process of manufacturing piston rings characterized by any and all of the novel 45 and useful characteristics hereinafter fully described.

Other objects of the invention will appear from the following description, reference being made to the accompanying drawings 50 illustrating rings in different stages of their manufacture, and in which—

Figure 1 is a side elevation of a ring

blank as it appears in a casting or is cut from a cylinder.

Fig. 2 is a side elevation of the ring blank 55 after it has been cut to provide an open resilient blank.

Fig. 3 is a view showing the partly formed ring on an arbor, upon which the structure and formation of the ring are changed and 60 the ring is conformed to a new shape.

Fig. 4 is a view showing the ring after it has been given its new conformation or shape upon the arbor and removed therefrom. 65

Fig. 5 is a side elevation of the finished ring.

Fig. 6 is a sectional view of a cylinder and piston after the finished ring is mounted 70 in connection therewith.

Figs. 7, 8, 9, 10 and 11 are elevations of a piston ring blank of the split type illustrating different stages through which the blank may be passed before being subjected to the final changes in conformation and shape, as 75 a result of which the principal objects of the invention are attained.

Figs. 12 and 13 are views illustrating the ring upon the arbor, upon which the structure and formation of the ring are changed 80 and the ring is given its final shape before being finished.

Fig. 14 is a side elevation of the finished ring.

Fig. 15 is a sectional view of a cylinder 85 and piston showing the finished split ring in connection therewith.

The unfinished ring blank illustrated in Fig. 1 may be in the form of a casting or cut from a blank or cylinder having an external 90 diameter equal to the internal diameter of the cylinder for which it is intended, plus the quantity of material to be removed in finishing the ring. When the unfinished ring blank illustrated in Fig. 1 is produced, 95 it is in the form of a complete uncut ring, and the next step in the manufacture of the ring, illustrated in Figs. 1 to 6, consists in cutting the ring as indicated at 1 in Fig. 2, in order to provide a ring of the open resilient type. This cut may be of any form, whether a straight cut, a diagonal cut, or a lap-joint cut, as preferred. In either instance the cut is made of very narrow width 100

so that the space between the ends of the ring is practically closed when the finished ring is compressed within the cylinder and upon the piston for which it is intended.

5 The open ring blank is then placed upon an arbor 2 (Fig. 3) which expands the ring to a size in excess of the cylinder for which it is intended by radial pressure imparted at several points. However, while the ends 10 of the ring are spread apart, the radii from the axis of the arbor to the ends of the ring remain approximately constant and unvaried, whereas the radii from the axis of the arbor to the portions of the ring intermediate of the ends to the first points of contact with the arbor are of progressively increasing length, it being understood that the points of contact of the arbor are on the same radii of curvature. Thus, the portion 15 of the ring which is subjected to expanding pressure by the arbor is on the same radii of curvature, whereas the portions of the ring between the ends thereof and the first points of contact with the arbor are on different radii of curvature which are approximately the same as the radii of curvature 20 of the original ring blank.

The ring is next subjected to heat while on the arbor until the structure thereof is 30 changed and corrected by rearrangement of the molecules in conformity with the new shape, so that when the ring is removed from the arbor it retains the size and shape given it thereby. The ring, after it has been subjected to heat and removed from the arbor, 35 as illustrated in Fig. 4, in which the dotted annular line 3 indicates the original internal diameter of the ring before being placed upon the arbor and subjected to the heat, is 40 turned and finished in any desired manner to produce the complete finished ring shown in Fig. 5. When this finished ring is placed upon a piston and compressed within the cylinder for which it is intended, it forms a 45 proper fit and imparts a uniform radial pressure against the cylinder all around.

The finished ring applied to the piston within the cylinder is illustrated in Fig. 6, the ends of the ring being brought nearly together, and the pressure of the ring against 50 the cylinder being approximately uniform throughout the entire circumference of the ring as a result of the conformation of the ring which is effected in the manner described.

The ring illustrated in Figs. 7 to 15 inclusive, is a split ring having its ends overlapping for a portion of its circumference and held together throughout their length 60 by the resiliency of the metal, and also having a conformation whereby the radial pressure of the ring is properly proportioned and equalized in order to obtain uniform pressure against the cylinder all around. The split ring is produced from an annular

blank and is cut to form a spiral slot 4 from a point near one edge of the ring to a diametrically opposite point near the opposite edge thereof as illustrated in Fig. 7. The next operation consists in cutting narrow slits or cuts through the edges of the ring opposite the ends of the spiral slot as indicated at 5, in order to provide a blank for an open resilient ring having overlapping ends. The ring is next inverted, as 75 illustrated in Fig. 9, by reversing the relative positions of the ends by passing one by the other, and the inverted ring thus produced is heated or hammered to correct and change the arrangement of the molecular 80 structure thereof in conformity with the new shape. Then, the ring is re-inverted to position the ends thereof on the same sides or faces originally occupied by them, which causes the overlapping ends of the ring to 85 press together by the resiliency of the metal, as illustrated in Fig. 10. Thereafter, the ring is faced on the side edges thereof in the usual way so that the ring is given a width to fit properly within the groove for which 90 it is intended.

The ring is then placed upon an arbor 6 which expands the ring to a size in excess of the cylinder for which it is intended by radial pressure imparted at several points. 95 The extremities of the overlapping portions of the ring are not expanded so that the radii of curvature of the overlapping portions adjacent to the ends thereof remain approximately constant and unvaried, whereas 100 the radii from the axis of the arbor to the portions between the ends and the first points of contact with the arbor are of progressively increasing length until they attain a length equal to the radii of curvature 105 of the remaining portions of the ring. Thus, the entire portion of the ring which is subjected to expanding pressure by the arbor is given an annular shape, whereas the extremities of the overlapping portions of the 110 ring between the ends thereof and the first points of contact with the arbor are circular arcs having substantially the same radii as the original ring blank.

The ring is next subjected to heat while 115 on the arbor, until the molecules thereof are changed in conformity with the new shape, so that when the ring is removed from the arbor it retains the size and shape given it thereby. The ring, after it has been subjected to heat and removed from the arbor, 120 as illustrated in Fig. 14, in which the dotted annular line 7 indicates the original internal diameter of the ring before being placed upon the arbor and subjected to heat, is 125 turned and finished in any desired manner, so that when placed upon a piston within a cylinder the ring forms a proper fit and imparts a uniform radial pressure against the cylinder all around.

Obviously the order of the operations in giving the ring its final shape is unimportant and may be varied within the scope of the appended claims.

5. What I claim and desire to secure by Letters Patent of the United States, is:—

1. The process of manufacturing piston rings, which consists in expanding annular, cut rings to a size in excess of the diameter 10 of the cylinder for which they are intended, leaving the end portions of the rings of approximately the same curvature as originally, and heating the expanded rings until the tension of the metal is changed and set 15 in the expanded shape.

2. The process of manufacturing piston rings, which consists in expanding annular rings to a size in excess of the diameter of the cylinder for which they are intended, 20 forming the end portions of the rings with approximately the same radii of curvature as originally, setting the tension of the rings in their expanded shape, and finishing the rings.

25. 3. The process of manufacturing piston rings, which consists in expanding ring blanks to a size in excess of the cylinders for which they are intended, leaving the end portions of the blanks curving to approximately the same radii of curvature in which they were originally, and setting the tension of the blanks in the shape aforesaid.

4. The process of manufacturing piston rings, which consists in applying pressure to 35 an annular ring to change the shape thereof to an eccentric ring of uniform radial thickness all around, and setting the tension of the metal in the eccentric shape.

5. The process of manufacturing piston 40 rings, which consists in changing the shape of an annular ring to an eccentric shape, setting the tension of the metal in the eccentric shape, and finishing the ring.

6. The process of manufacturing piston 45 rings of uniform radial thickness, which consists in changing the shape of an annular ring to one in which the greater segmental portion thereof is concentric, and the end portions are eccentric with respect to the 50 greater portion, and setting the tension of the metal in the shape aforesaid.

7. The process of manufacturing piston 55 rings, which consists in applying pressure to a cut ring to give the greater portion thereof an expanded concentric shape, and leaving the lesser portions thereof adjacent to the

cut of the same radii of curvature as originally, and subjecting the ring to heat to set the metal in the shape aforesaid.

8. The process of manufacturing piston 60 rings, which consists in reshaping a cut, unfinished, concentric ring, to a shape in which the ends are of shorter radii of curvature than the remaining segmental portion of the ring, subjecting the ring to heat to set the 65 tension thereof in the new shape, and turning the ring to size.

9. The process of manufacturing piston 70 rings, which consists in mechanically expanding a circular blank so that one segment thereof is of shorter radius of curvature than the adjacent portion, setting the ring in its expanded shape, and then finishing the ring while in the expanded shape.

10. The process of manufacturing piston 75 rings, which consists in mechanically expanding a circular metallic blank having a cut therethrough, so that the segments of the ring adjacent to the cut are in the form of arcs whose centers are different from each 80 other and from the center of the remaining portion of the ring, heating the ring to set the blank in the expanded shape, and then finishing the ring to size.

11. The process of manufacturing piston 85 rings, which consists in mechanically expanding an open, circular, metallic, unfinished blank, so that the segments of the blank extending at each side of the cut are of approximately the same radii of curvature as originally and the remainder of the blank of greater radius of curvature, then 90 fixing the blank so that it will remain set in the expanded shape, and then finishing the ring to size.

12. The process of manufacturing piston 95 rings, which consists in deflecting an open, annular, metallic blank so that the open ends of the blank are out of the curvature of the remaining portion thereof and setting the 100 blank in said shape, then machining the blank to size to produce a finished ring having equal radial pressure throughout its length.

In witness whereof, I have signed this 105 specification in the presence of two subscribing witnesses.

HARRY S. FRANK.
